W. Pomeroy,

Truss,

N° 63,091

Patented Mar 19, 1867.

Fig:1

Fig:2

Diagram of a mechanical component labeled 'Fig: 3.' The component consists of a central vertical shaft with a cross-shaped slot. A horizontal plate labeled 'G' is attached to the top of the shaft. A vertical plate labeled 'H' is attached to the side of the shaft. Two small circles labeled 'Z' and 'Z'' are at the bottom of the shaft.

United States Patent Office.

WILLIAM POMEROY, OF NEW YORK, N. Y.

Letters Patent No. 63,091, dated March 19, 1867.

IMPROVEMENT IN TRUSSES.

The Schedule referred to in these Letters Patent and making part of the same.

TO ALL WHOM IT MAY CONCERN:

Be it known that I, WILLIAM POMEROY, of the city, county, and State of New York, have invented a new and useful Improvement in Hernia Truss; and I do hereby declare that the following is a full, clear, and exact description thereof, which will enable others skilled in the art to make and use the same, reference being had to the accompanying drawings, forming part of this specification, in which—

Figure 1 is an under side view of my improved truss.

Figure 2 is a detail sectional view of the rupture pad, taken through the line *x x*, fig. 1.

Figure 3 is a detail sectional view, taken through the line *y y*, fig. 1.

Similar letters of reference indicate like parts.

My invention has for its object to furnish an improved truss, so constructed and arranged as at the same time to give an upward and inward pressure; second, which may be lengthened or shortened so as perfectly to adjust the pad to the hernia; and, third, which will not allow the movements of the body to interfere with the position of the pad over the hernia; and it consists, first, in the construction, combination, and arrangement of the pad-spring with the pad and with the main-spring of the truss; and, second, in the combination of the slide or clasp and set-screw with the parts of the main-spring of the truss, the whole being constructed and arranged as hereinafter more fully described.

A is the back-pad, to the centre of which is pivoted the end of the main truss-spring B, by means of a set-screw, C, which passes through a hole in the end of the spring B, and screws into a nut set in the body of the pad A. Several holes may be made through the end of the spring, so that the position of the pad A may be changed to fit the truss to larger or smaller bodies. D is a keeper, attached to the side of the pad A, through which the spring B passes, and which prevents the said pad from revolving. E is the hernia pad, which is made of wood, and very nearly in the shape of the half of an egg, divided by a plane passing through its longer axis, as shown in fig. 2. To the flat surface or side of the pad E, near its lower or broader end, is securely attached the end of the pad-spring F. This spring is made in about the shape represented in figs. 1 and 2, and its upper end is pivoted to the end of the main-spring B, as shown in fig. 2, so that the pad E may maintain its position upon the hernia, however the spring may be moved by the movements of the body. The main-spring B may be made in one piece, or it may be made in two, if desired. This latter construction I prefer, as it enables the pad E to be accurately adjusted to the position of the hernia. In this case a clasp or slide, G, is made in the form represented in figs. 1 and 3, which is securely riveted to the end of the part *b¹* of the spring B. The part *b²* of the spring B is then slid into the groove of the clasp G, and it is held in any desired position by means of the set-screw H, which passes through a hole in the clasp G and end of the part *b¹* of the spring B, and presses the part *b²* of said spring against the flanges of the clasp G firmly, securing it in place. The part *b¹* of the spring B, between the pad A and the clasp G, may be covered with leather, I, or other suitable material, to prevent it from chafing the body of the wearer. J is a strap, designed to secure the truss in position upon the body of the wearer. One end of the strap J is secured to the pad A by having the set-screw C pass through it. The other end has holes formed through it, and it is adjusted and secured in place by passing the projecting end of the pivot K through one of said holes, as shown in fig. 1.

Having thus described my invention, I claim as new, and desire to secure by Letters Patent—

The construction, combination, and arrangement of the pad-spring F with the pad E and main-spring B of the truss, substantially as herein described and for the purpose set forth.

WILLIAM POMEROY.
